BASE-BOARD RADIATORS

Allan W. Lundstrum, % Ohio Fuel Gas Co.,
99 N. Front St., Columbus, Ohio

Filed Sept. 19, 1957, Ser. No. 685,036

6 Claims. (Cl. 257—133)

This invention relates to radiators for space heating and more specifically to a novel and improved heat radiator for heating homes, offices and the like that is particularly useful as a so-called base-board radiator.

Many types of radiators for space heating have been proposed and known structures have not been found entirely satisfactory for a number of reasons, among them being the relatively high cost of manufacture and installation. While base-board radiators are generally fabricated in sections, each section is generally formed of a number of individual components for assembly when the equipment is installed. This greatly complicates installation procedures and adds materially to the cost of the heating plant. Other disadvantages of prior known radiators of the base-board type include the relatively inefficient utilization of space to obtain maximum transfer of heat to the ambient air, the relatively complicated mounting procedure and the requirement of special tools and equipment for assembly and joinder of the sections.

The above and other disadvantages of prior radiators are overcome with this invention which is characterized by its simplicity, ease of installation, and improved efficiency and appearance.

Another object of this invention is to provide a basic heat exchanger section of utility especially in and for sectional base-board radiators and incorporating on one attractive die cast part a channel for a heat carrying fluid, a channel for directing air being heated across the heated surface, sturdy and damage-resistant heat conducting fins, and a mounting therefor which will enable substantially unrestricted expansion and contraction of the section or sections due to temperature changes.

Another object of the invention resides in the provision of a sectional base-board radiator employing such basic sections that affords efficient utilization of space for maximum transfer of heat to the air and whose sections are provided with improved telescopic connectors which greatly facilitate coupling the sections one to the other so that they may be joined together using a drive fit joint with suitable adhesive sealant and desired lengths achieved without cutting, fitting, threading, welding or soldering.

Still another object of the invention is the provision of an improved sectional base-board radiator wherein each section constitutes a complete, substantially unitary structure that can be readily attached to adjoining sections and to a supporting wall and is so constructed and arranged as to direct heat away from the wall to prevent wall streaking.

A further object of the invention resides in the provision of novel input and output terminal sections for such improved basic heat exchanger sections, which are die cast and permit easy and quick connection to such sections and which make possible easy and quick connections to fluid conducting tubes or pipes either from below through the floor or from the back through the wall, whichever is more convenient, with minimum labor and structural changes.

A still further object of the invention resides in the

2

provision of a simple and inexpensive valve as a part of one terminal.

The above and other objects and advantages of the invention will become more evident from the following 5 description and accompanying drawings forming part of this application.

In the drawings:

Figure 1 is a front elevational view of a sectional base-board radiator in accordance with this invention;

10 Figure 2 is an enlarged fragmentary front view in partial section of the base-board radiator of Figure 1;

Figure 3 is a cross sectional view of the input valving means taken along the line 3—3 of Figure 1;

15 Figure 4 is a cross sectional view taken along the line 4—4 of Figure 2;

Figure 5 is a top view of the input terminal means of Figure 2 with the valving means removed;

Figure 6 is a top view of the output terminal of Figure 2;

20 Figure 7 is a side elevational view of the input terminal taken in the direction of the arrows 7 of Figure 5;

Figure 8 shows a side elevational view of the output terminal taken in the direction of arrows 8 of Figure 6;

25 Figure 9 is a rear view of a heat exchanger section of the base-board radiator of Figure 1;

Figure 10 is a cross sectional view taken along the line 10—10 of Figure 9;

Figure 11 is a cross sectional view of the heat exchanger section taken along the line 11—11 of Figure 9;

30 Figure 12 is a front elevational view of a modified embodiment of the invention;

Figure 13 is an enlarged fragmentary section of the embodiment of Figure 12 illustrating the coupling of a 35 radiator section to the input terminal section;

Figure 14 is an enlarged fragmentary section of the embodiment of Figure 12 illustrating the coupling between a radiator section and the output terminal section;

Figure 15 is a cross sectional view taken along the 40 line 15—15 of Figure 13; and

Figure 16 is a cross sectional view of Figure 14, taken along the line 16—16 thereof.

Referring to Figure 1, the base-board radiator in accordance with the invention is denoted by the numeral

45 20 and includes a heat exchanger having a plurality of similar heat exchanger sections 24a to 24d, an input terminal 26 for connecting the heat exchanger to a fluid inlet pipe 32, and an output terminal 28 for connecting the heat exchanger to a fluid return 34. The heat exchanger sections 24a through 24d are coupled to each other by telescopic coupling means 30b, 30c and 30d. Similar coupling means 30a and 30e connect the heat exchanger sections to the input terminal 26 and to the output terminal 28. Since the heat exchanger sections 24a through 24d and the coupling means 30a through 30e are substantially identical, it is possible to assemble a base-board radiator using any desired number of sections in series with the ends being terminated by the terminal members 26 and 28.

60 More specifically and with reference to Figures 2 through 11, each heat exchanger section 24a through 24d includes a conduit 40, a plurality of fins 42, a deflector 44 and a mounting hole 46. Each section is preferably fabricated by die casting with the conduit 40 and

65 the fins 42 formed integrally one with the other. The conduit 40 for the heated fluid is tapered in plan as will be observed from Fig. 4. It has its smallest section in the center and gradually increases in size toward both ends, thus permitting the core used in the die casting to be withdrawn. Notwithstanding this gradually increasing across-section, the front and rear walls of the heat exchanger section are maintained at a substantially uni-

form thickness over substantially the length of the conduit, thus ensuring the preservation of maximum strength and most efficient utilization of the die casting material. It will be observed from Fig. 4 that the heat radiating fins 42 though co-planar insofar as their tips are concerned, are of greatest length at the center of the section in conformity with the preservation of the uniform wall thickness over the length of the section. The fins 42 essentially define the contour of the section with the conduit 40 disposed near the front to form a relatively long path for the circulation of air therethrough and thus utilize the space occupied by the radiator most effectively and efficiently. Moreover, with the integral construction of the conduit 40 and fins 42, maximum transfer of heat to the fin surfaces is obtained. The top of each section 24a to 24d is at least partially closed by a deflector 44 integrally formed with the fins 42. With this arrangement the heated air is deflected outwardly away from the wall to minimize soiling of the wall surface above the radiator and additional mechanical support is afforded the fins 42.

Each heat exchanger section 24a through 24d includes longitudinally elongated and preferably recessed mounting hole 46 extending therethrough to accommodate a screw or bolt (not shown) for fixing each section 24 individually to the wall or wall baseboard in the assembly of the base-board radiator 20. The elongation of the mounting hole 46 is shown more clearly in Figure 2, the hole being formed when the section is cast. In this way complicated mounting means are avoided and contraction and expansion of the section or sections due to temperature changes is allowed for.

In order to facilitate quick and easy connection of the sections 24a, 24b, etc. one to the other and to the end terminals, each section is provided at its ends with tapered male and female end connectors denoted by the numerals 36 and 38, respectively. The male connector part 36 is die cast integrally with its associated radiator section and has an opening corresponding to the shape and area of the opening of conduit 40. The female connector part 38 is in the form of a tapered opening 38 for telescopically receiving the male connector part 36 of an adjoining section in a drive fit joint to form a water-tight seal with a continuous, uninterrupted passage through both sections. Preferably, a suitable heat resistant adhesive sealing compound is used in the joints to insure a more positive seal. It will be observed that any desired length of radiator may thus be obtained by coupling the basic heat exchanger sections together without cutting, fitting, threading, welding or soldering.

The input terminal section 26 which controls the flow of heated fluid to the heat exchanger comprises essentially a hollow tapered male connecting member 36a communicating with an exit passage 50 to permit flow to the heat exchanger, bottom and back entry ports 52, 54, respectively, for accepting heat carrying fluid from a supply pipe 32, and a tapered or conical valve chamber 56.

The male connecting member 36 is adapted to be seated in the tapered opening 38 of the heat exchanger section 24 in a drive fit joint in the same manner as one section 24 is connected to the next.

The input terminal section also comprises a rotatable valve member 58 which is in the form of a truncated cone as shown and seats in the conical chamber 56. The lower end of the valve member 58 is spaced from the bottom of chamber 56 which communicates with the inlet openings 52 and 54. The valve member 58 has a longitudinal channel 60 therein with a vertical cross sectional area at the conical surface of the valve matching the vertical cross sectional area of the exit passage 50. When the valve member 58 is rotated 90° from its closed position shown in Figure 2 into a position with the slot or channel 60 aligned with the exit passage 50, fluid may flow freely from one or the other of the inlets 52 and 54

through the channel 60 into the passage 50 and thence to the radiator section. A shaft 62 coaxial with the valve couples the valve member with a handle 64 to enable manual rotation of the valve on its axis, the valve being held in recess 56 by a coil spring 66 and packing nut 68, the latter threadedly engaging collar 69. The conical valve member 58 and its stem 62 are preferably integral and preferably fabricated as a unit from a heat resistant plastic to permit a smooth self-lubricating rotation. The input terminal section is preferably die-cast in the same manner as the radiator sections. By reason of the improved arrangement of valve elements in terminal 26, two or more inlet openings 52 and 54 may be provided to facilitate connection of the radiator to the heating system. In the illustrated embodiment, either of inlets 52 and 54 may be used for making connection with supply pipes of the heating system. As shown in Figure 1 the supply pipe 32 extends upwardly through the floor to connect with inlet 52 but it may extend forwardly through the wall, so as to connect with the back inlet 54. In either case the unused inlet would be plugged as by means of a suitable threaded plug (not shown), the inlet being suitably threaded, as shown, to receive the plug. Thus, the installation of the radiator is not restricted to a particular mode of connection, and there is no need for conventional coupling means such as elbows and the like.

The outlet terminal section 28 for returning heat carrying fluid from the terminal heat exchanger section to the fluid return pipe 34 includes a tapered opening 38a for accepting a tapered male connecting member such as the connector part 36 of a radiator section 24, an entry port 70 for receiving fluid from the enclosed channel 40 of the adjoining radiator section, exit port 72 and 74 for connecting the terminal to an outlet pipe such as pipe 34 of Figure 1 and a chamber 76 interconnecting the entry port 70 to the exit ports. Figures 6 and 8 illustrate the outlet terminal 28 and show the right angular relationship between the exit ports.

A modified base-board radiator 20 is shown in Figure 12 and includes improved locking means 80 for holding the sections 24 and terminals 26 and 28 in position one relative to the other. As embodied in the basic radiator sections, the locking means consists of a slot in one end of the basic section and a lip on the other end. When two adjacent sections are telescoped together the lip can be sprung or driven into the slot to prevent the sections from being pulled apart. This will relieve the adhesive sealant of any strain in tension. Figure 13 to 16 show details of this improved feature.

The coupling locking means 80 shown in Figs. 13 and 15 includes a groove 82 spaced from the base of the tapered connecting member 36a by an inclined ramp 85. A tab 88 extends from the front wall of the adjoining radiator portion and has a vertical groove 83 spaced from the end to form a tapered latching member 84 whose front face 86 is a prolongation of the wall 38 of the connector 36. When a drive fit joint is being established, the latch 84 is sprung slightly outward and rides over the inclined surface of the tapered member 26 and the ramp 85. When the adjoining radiator sections are properly connected the latch 84 engages the groove 82 to secure the connected sections one to the other.

Figures 14 and 16 illustrate this latching arrangement as applied to the opposite end of a basic section 24 and terminal 28. The elements of these figures corresponding to elements of Figures 13 and 15 have been designated by like primed numerals. It will be understood that the locking means 80b, c and d for connecting the successive radiator sections one to the other are similarly constructed.

With the locking means as described above, the radiator sections are firmly and positively secured one to the other and will not separate even when subjected to continued vibration of sudden changes in temperature and

the adhesive sealant is relieved of any strain in tension.

While only certain embodiments of the invention have been described, it is apparent that modifications, alterations and changes may be made without departing from the true scope and spirit of the present invention as defined by the appended claims.

What is claimed is:

1. A base-board radiator comprising: a die cast inlet terminal section having a tapered male connector part and having valve means including a tapered valve member and a tapered valve seat therefor, for regulating the flow of heated fluid to the base-board radiator; a die cast outlet terminal section for discharging fluid from the base-board radiator, said outlet terminal having a tapered female connector part; and a plurality of finned radiator sections coupled together in end-to-end relation and to said inlet and outlet terminal sections, each said radiator section including die cast top, bottom, front and rear walls integral with each other and spaced apart to form an elongated substantially smooth-bored fluid conduit extending lengthwise of the section from end-to-end thereof, said conduit gradually increasing in size from the center toward both ends and terminating at its one end in an internally tapered female connector part, and at its other end in an externally tapered male connector part, said male and female connector parts being coaxially aligned with each other and with the lengthwise axis of said conduit, and said top, bottom and rear walls only having, exteriorly, a set of die cast tapered heat radiating fins integral therewith, said fins being generally parallel to each other and perpendicular to the lengthwise axis of said conduit, said fins also extending generally rearwardly from said front wall to and beyond said rear wall, and having side walls which are converging in the direction from front to rear, said inlet terminal having its male connector part sealingly, telescopically received in the tapered female connector part of the first of said radiator sections, and said outlet terminal section sealingly, telescopically receiving in its tapered female connector part the tapered male connector part of the last of said radiator sections.

2. A base-board radiator in accordance with claim 1 in which the front and rear walls of each radiator section are of substantially uniform thickness over substantially the length of said conduit.

3. A base-board radiator in accordance with claim 1 in which the front and rear walls of each radiator section are provided each with an aperture for the passage of a fastening device from front to rear of the section, the

apertures being interconnected and sealed off from said conduit by a hollow bridging member integral with said walls.

4. A base-board radiator in accordance with claim 1 in which the set of heat-radiating fins is provided with a deflector member for deflecting heated air away from an adjoining wall, said deflector member being disposed along the top edge of the fins of said set and integrally connected thereto.
5. A base-board radiator section comprising die cast top, bottom, front and rear walls integral with each other and spaced apart to form an elongated substantially smooth-bored fluid conduit extending lengthwise of the section from end-to-end thereof, said conduit gradually increasing in size from the center toward both ends and terminating at its one end in an internally tapered female connector part, and at its other end in an externally tapered male connector part, said male and female connector parts being coaxially aligned with each other and with the lengthwise axis of the conduit, and said top, bottom and rear walls only having exteriorly a set of die cast tapered heat radiating fins integral therewith, said fins being generally parallel to each other and perpendicular to the lengthwise axis of said conduit, extending generally rearwardly from said front wall to and beyond said rear wall, and having side walls which are converging in the direction from front to rear.
6. A base-board radiator section in accordance with claim 5 in which said front and rear walls are of substantially uniform thickness over substantially the length of said conduit.
